UNITED STATES PATENT OFFICE.

DAVID J. HAUSS, OF CINCINNATI, OHIO, ASSIGNOR OF ONE-HALF TO
JOHN J. CUSHING, OF SAME PLACE.

ELECTRIC-MOTOR CONTROLLER.

SPECIFICATION forming part of Letters Patent No. 678,664, dated July 16, 1901.

Application filed March 5, 1901. Serial No. 49,682. (No model.)

To all whom it may concern:

Be it known that I, DAVID J. HAUSS, a citizen of the United States, residing at Cincinnati, in the county of Hamilton and State of Ohio, have invented certain new and useful Improvements in Electric-Motor Controllers; and I do hereby declare the following to be a full, clear, and exact description of the invention, such as will enable others skilled in the art to which it appertains to make and use the same.

My invention relates to improvements in electrical controllers for street-railway and other motors; and one of its objects is to prevent 15 sparking and burning of contacts of the controllers, the motors, and connections and preventing destruction of insulation.

Another object is to provide an improved controller for directing the current through 20 the motors.

Another object is to provide a controller which dispenses with dead resistance and employs only live resistance in controlling the motors, thereby simplifying the apparatus.

Another object is to provide a more simple 25 and reliable controller and reversing mechanism.

Another object is to provide a tripping device whereby the controller-lever can only be 30 thrown one notch at a time, thereby preventing a jerky movement of the car and an undue strain on the motors and car.

My invention also consists in certain details of form, combination, and arrangement, 35 all of which will be more fully set forth in the description of the accompanying drawings, in which—

Figure 1 is a diagram of the controller, motors, reversing - switches, connections, and 40 other mechanism as employed in connection with my improved controller. Fig. 2 is a diagram of the motors, showing the successive connections effected by the controller. Fig. 3 is a horizontal sectional view through the 45 controller-box, showing the arrangement of the contacts therein. Fig. 4 is a section on line $z z$ of Fig. 5, showing the automatic circuit-breaking mechanism. Fig. 5 is a plan view of the lower carbon and magnetic blow-out coil of the same. Fig. 6 is a plan view of the mechanism for dogging the controller to

prevent the too-rapid application of a strong current through the motors. Fig. 7 is a vertical section through the same on line $v v$ of Fig. 6. Fig. 8 is an end view of the finger 55 and dash-pot.

It is customary in street-cars, motor-vehicles, and for similar purposes to connect the electric motors in series and parallel successively, as shown in Fig. 2, thereby successively reducing the internal resistance and increasing the amount of current, and thereby the power of the motors. At the instant of changing from each system of connections to the succeeding one there is a tendency to 65 spark and arc across the various connections, as well as to destroy the insulation of the motors, which has been prevented heretofore by the introduction of dead resistance into the circuit during the transition. By means of 70 the controller herein described I dispense with this dead resistance as well as the necessity of carrying the same on the car and the mechanism for cutting it into and out of the circuit.

E represents a cylinder, of insulating material, (see Fig. 3,) mounted on a stem E', which is journaled in the controller-box I.

A B C D represent respective series or sets of contact-blocks, which are bedded into the 80 cylinder E and adapted to be turned so as to bring any one of said sets of contacts beneath the contact blocks or brushes 1 2 3 to 15, which are stationary, being held in contact with the surface of the cylinder by means of 85 spring-arms F.

G represents a cylinder journaled on a stem G' and carrying a series of contacts J J', which when the switch-lever H is turned are adapted to alternately contact with the brushes or 90 blocks 16 to 23, which serves to reverse the direction of the motors. As the motors can be safely reversed only when the current is cut off, I provide a disk K, mounted on the shaft of the controller-cylinder and provided 95 with a notch K'.

L represents a disk in the same horizontal plane as the disk K and mounted on the shaft of the reversing-switch. The disk L is provided with two notches L', so arranged that 100 the controller can be turned when either of the notches L' is opposite the periphery of

the disk K and so that the disk L and reversing-switch can only be turned when the notch K' is in the position shown in Fig. 3 and the current cut off from the motors.

5 In order to prevent the controller-lever from being turned two or more notches or spaces at a time while applying the current, I provide a dogging mechanism, which in its preferred form consists of a series of pawls 10 M, pivoted to an annular frame M' at one end and provided at their free ends with springs N to normally hold the free ends of the pawls against the stop-pins N', which brings the free ends of the pawls into the 15 path of a finger or arm O, which projects from and travels with the stem E'. O' represents a roller which is pivoted at the end of the stem P of a dash-pot plunger P', which is adapted to reciprocate in the cylinder Q. Q' 20 represents a spring forcing the plunger out. R represents the cylinder-head, which is provided with an air-escape passage R', the orifice in which is regulated by means of the screw S. S represents a valve in the plunger to permit 25 the ready introduction of air in front of the plunger. U represents an annular cam-surface, against which the roller O' bears. This mechanism is preferably located near the bottom of the controller-box, but may be 30 located just beneath the top or cover, if desired. It is also evident that the dash-pot and other mechanism might be set vertically, if desired.

U' represents a set-screw seating in a groove 35 in the face of the plunger to prevent the same from turning in the cylinder Q.

As the controller-lever is turned the finger O strikes the end of the first pawl, bringing the controller-lever to a stop, the spring Q', 40 however, acting upon the plunger P', causing the air to escape from the forward end of the cylinder Q, whereupon the roller O', which is opposite a notch in the cam-face U, forces the pawl back out of the path of the finger O, permitting the controller to be turned another notch, the interval of time elapsing being sufficient to permit the motors and car to acquire a velocity suitable for the introduction of a heavier current.

50 As shown in Fig. 1, the several series of contacts A B C D are adapted to be successively brought into contact with the brushes or contacts 1 to 15. When the contacts 1 to 15 are in contact with the series A, the motors and their fields are all connected up in series, as shown in the upper diagram of Fig. 2, and the current travels as follows: from the line-wire through the trolley T to brush 11, thence by wire 24 through the field-coil 25, returning to brush 13 through sliding contacts 26 27 to brush 12, wire 28 through field-coil 29 to brush 14, through the sliding contacts 30 31 and brush 15 and wire 32 to switch-brush 22, by contact J, brush 23, and wire 33 65 through armature 34 to brush 20, through contacts J, brush 21, and wire 35 to brush 5, through contacts 36 37, brush 6, wire 38, and

field-coil 39 to brush 8, through contacts 39' 40, brush 7, wire 41, and field-coil 42 to brush 9, through contacts 43 44 to brush 10, wire 45 to brush 18, through contacts J, brush 19, wire 46, and armature 47 to brush 16, through contacts J to brush 17, and wire 48 to brush 4. From brush 4 the current passes to the blocks 49 50 51 52 to brush 1 and thence to 75 the earth at E.

It will be noted that the blocks 49, 50, 51, and 52 are successively narrower and that as these blocks turn under the brushes the contact through 52 and 1 is first broken, the current being maintained through 51 2 and the magnetic blow-out coil 53 to 1 and the earth. As contact is broken at 51 and 2 the current is maintained through 50 3, the line 54, the supplemental field-coils 55, the blow-out coil 53, 85 and brush 1 to the earth. As the contact is broken at 50 and 3 the current is established through 49 4, line 56, the carbons 57 58, the magnetic coil 59, brush 3, line 54, coils 55 and 53 to brush 1 and the earth, the passage of the current through coils 55 increasing the density of the magnetic field, which increases the counter electromotive force in the armatures, while the magnetic blow-out coil, which may consist of one or more sections wherever needed, serves to prevent and to break any arc formed, while the current as soon as it passes through the coil 59 pulls down the armature or solenoid 60, thereby creating a gap and arc between the carbons 90 57 58, which is acted upon by the blow-out coil 53 to break the arc and cut off the current, after which the carbons 57 58 automatically come together and establish connection between 3 and 4 ready for another operation. 95

When the series of contacts B are moved opposite the brushes 1 to 15, the motors are connected up in parallel, as indicated in the second diagram of Fig. 2, in which case the current travels as follows: from T to 11, 110 where it branches, one branch passing through 24 25 13 65 63 to 64 and the other branch through 61 62 12 28 29 14 63 to 64, thence by single line through 15 22 23 33 34 20 21 35 5 to 66, where it again branches, one branch 115 passing through 67 6 38 39 8 to 68, the other branch passing through 67' 7 41 42 9 to 69, thence by single line through 70 10 45 18 19 46 47 16 17 to 4, and by 71 72 73 74 to 1.

When the series of contacts C is moved opposite the brushes 1 to 15, the motors are connected up as indicated in the third diagram of Fig. 2, in which case the current is established as follows: It branches at 11, one line being through 24 25 13 75 76 12 28 29 14 77 78 15 22 23 33 34 20 21 35 to 5. The other line passes from 11 to 79 80 81 82 83 6 38 39 8 84 85 7 41 42 9 86 87 10 18 19 46 47 16 17 to 4, and thence the two lines pass together through 88 89 90 91 92 to 1.

When the series D is moved opposite the brushes 1 to 15, the motors are connected up as indicated in the lower diagram of Fig. 2, and the current travels as follows: Four

branches are formed, the first from 11 through 24 25 13 to 93, the second from 11 through 80 96 12 28 29 to 14 and 94, thence the first and second jointly through 95 15 22 23 33 34 20 21 5 35 to 5. The third branch passes from 11 through 80 81 7 41 42 9 96 to 97. The fourth branch passes from 11 through 80 81 82 6 38 39 8 to 98. Thence branches three and four pass jointly from 97 through 10 18 19 46 47 16 10 17 48 to 4, and thence all the branches pass through 99 100 101 102 103 to 1.

Each time as the brushes leave the upper blocks of the series A B C D the successive brushes 1 2 3 are cut out one at a time and 15 the current broken by the automatic circuit-breaker before the brushes 4 to 15 leave the balance of the contact-blocks.

The mechanism for automatically breaking the circuit may be variously constructed with 20 departing from the general principle of my invention and may, if desired, be so arranged as not to break the circuit during the operation of cutting in the current.

In Figs. 4 and 5 I have shown the preferred 25 form of construction, in which 58 represents the upper carbon; 57, the lower carbon; 53, the magnetic blow-out coil; 104 105, magnetic poles creating a magnetic field across the face of the lower carbon. 106 represents the stem 30 of the upper carbon, which passes through a hole in the plate 107. This plate normally rests at one edge upon the stop-lug 108 and at the opposite edge upon the end of the lever 109, which lever is pivoted at 110 and provided at its opposite end with an armature 111, adapted to be acted upon by the electro-magnets 112, which tilts the lever 109 and lifts the plate 107, which binds upon the stem 106, and thereby lifts the upper carbon and 40 breaks the circuit. As soon as the circuit is broken the upper carbon and other parts drop back to normal position again ready for use.

The supplemental field-coils 55 serve the 45 double purpose of increasing the strength of the magnets at the instant of cutting in the current, thereby increasing the counter electromotive force in the motor, which materially assists in starting the motors, and at 50 shutting off the current in the motors is again cut into circuit, increasing the magnetic density of the field, and thereby increasing the counter electromotive force and reducing the amount of current passing through the motors 55 just prior to the breaking of the circuit.

Having described my invention, what I claim is—

1. In a controller for electric motors, a series 60 of stationary contacts; connections leading therefrom to the motor; the field-coils, and the source of electricity; a blow-out coil; a circuit-breaker separate from the controller; a series of sliding contacts adapted to cut the motor into and out of circuit; and means for 65 cutting the blow-out coil into the circuit before breaking the motor-circuit at the sliding contacts.

2. In a controller for electric motors, a series of stationary contacts; connections leading therefrom to the motor, the field-coils, and 70 the source of electricity; a blow-out coil; a circuit-breaker separate from the controller; a series of sliding contacts adapted to cut the motor into and out of circuit; and means for cutting the blow-out coil and circuit-breaker 75 into circuit before breaking the motor-circuit at the sliding contacts.

3. In a controller for electric motors, a series of stationary contacts, connections leading therefrom to the motor, the field-coils, and 80 the source of electricity; a blow-out coil; a circuit-breaker separate from the controller; and a series of sliding contacts of different lengths adapted to connect and disconnect the motor, and in so doing to first cut out the 85 current in its direct path and thereby force it through the blow-out coil and circuit-breaker to break the circuit before contact is broken at the sliding contacts.

4. In a controller for electric motors, a series 90 of stationary contacts; electrical connections leading therefrom to the motors, the field-coils, and the source of electricity; a magnetic blow-out coil; a supplemental field-coil; an automatic circuit-breaker; and a series 95 of sliding contacts of different lengths adapted to make and break the connections to the motor, and in breaking the connections to first cut out the current through the direct path and force it through the blow-out coil, 100 the supplemental field-coil, and the circuit-breaker, substantially as specified.

5. In a controller for electric motors, a series of stationary contacts; electrical connections therefrom to the motor, the field-coils, and the 105 source of electricity; a magnetic blow-out coil; a supplemental field-coil; a circuit-breaker; and a series of sliding contacts of different lengths adapted to make contact between the stationary contacts and to successively cut 110 into the circuit the blow-out coil, the supplemental field-coil, and the circuit-breaker.

6. In combination with a series of electric 115 motors, a series of stationary contacts; electrical connections leading therefrom to the motors, the field-coils, the reversing-switch, and the source of electricity; a magnetic blow-out coil; a series of supplemental field-coils; a circuit-breaker; and a series of sliding contacts of different lengths adapted to 120 connect the motors up in series and parallel, and when breaking the circuit to successively cut into the circuit the blow-out coil, the supplemental field-coils, and the circuit-breaker, substantially as specified. 125

7. In combination with a series of electric 130 motors, a series of stationary contacts; electrical connections leading therefrom to the motors, the field-coils, and the source of electricity; a magnetic blow-out coil; a series of supplemental field-coils; a circuit-breaker; and a series of sliding contacts adapted to connect the motors up in series and parallel, and when breaking the circuit to successively

cut into the circuit the blow-out coil, the supplemental field-coils, and the circuit-breaker, substantially as specified.

8. In a controller for electric motors, a series of stationary contacts; a series of electrical connections leading therefrom to the motor; the field-coils, and the source of electricity; a series of sliding contacts adapted to successively connect up the stationary contacts to put the motor and field-coils in series and parallel; an arm traveling with said sliding contacts; a series of pawls; a cam; a dash-pot

plunger adapted to act against said cam, and to force the pawls out of the path of the traveling arm to insure a step-by-step movement of the sliding contacts in one direction; substantially as specified.

In testimony whereof I have affixed my signature in presence of two witnesses.

DAVID J. HAUSS.
